UNITED STATES PATENT OFFICE.

BERT R. BENJAMIN, OF OAK PARK, ILLINOIS, ASSIGNOR TO INTERNATIONAL HARVESTER COMPANY OF NEW JERSEY, A CORPORATION OF NEW JERSEY.

BINDING MECHANISM.

1,200,455.

Specification of Letters Patent. Patented Oct. 10, 1916.

Application filed January 31, 1916. Serial No. 75,402.

To all whom it may concern:

Be it known that I, BERT R. BENJAMIN, a citizen of the United States, residing at Oak Park, in the county of Cook and State of Illinois, have invented certain new and useful Improvements in Binding Mechanisms, of which the following is a full, clear, and exact specification.

My invention relates to binding mechanisms.

It has for its object to improve the construction of such mechanisms and particularly the clutch tripping mechanism thereof in such a manner as to simplify and cheapen the mechanism, reduce the movement and wear of the trip stop, reduce the amount of necessary vibration of the trip arm, enable tighter bundles to be bound for a given pressure of the trip, reduce the friction in driving home the binder mechanism, minimize the adjustment necessary for wear, and provide a stronger construction which avoids wrong adjustment in the field.

These and other objects of my invention are attained by an improved construction wherein a stop is pivoted on the frame and connected to a bodily movable trip shaft in such a manner that upon bodily movement of the latter, the stop is oscillated about its pivot out of engaging position with the dog and held out of that position by coöperating means until the dog has completed its second revolution, whereupon the stop is again returned to dog engaging position.

In the accompanying drawings I have, for purposes of illustration, shown one embodiment which my invention may assume in practice.

In these drawings: Figure 1 is a front view of a binding mechanism equipped with my improvement, showing the parts in dog-engaging and releasing position. Fig. 2 is a view similar to Fig. 1 showing the parts in the position occupied by them during the discharge of a bundle. Fig. 3 is a detail plan view of the trip stop. Fig. 4 is an end view of the trip stop mechanism.

As in the usual construction, a binder frame or head 1 is disposed over the deck 2 of the binder. Upon the head is carried the usual binder mechanism including the needle 3 and discharge arms 4, the needle being connected to the usual needle shaft 5 and

through a link and crank connection 6 with a cam wheel 7 which is mounted on a rotating shaft 8 carrying the discharge arms 4. Coöperating with a cam 9 carried by the wheel 7 is a cam engaging member or roller 10 connected through a member 11 with a link 12, which is in turn connected to a crank 13 on the compressor trip shaft 14 carrying the compressor trip 15. As in the construction described in my previous Patent, No. 994,711, this shaft 14 is bodily movable relative to the binder head 1 when the trip is actuated and means are connected thereto engageable with the rotating dog 16 of a binder clutch 17 which connects the binding and discharging mechanism to the power shaft 18.

In my improved construction a trip stop 19 is pivoted at 20 upon an extension 21 on the binder head 1. This trip stop is provided with a grainwardly extending portion 22 engageable in extreme upper position with a lug 23 on the head 1, and this portion 22 is provided with a laterally extending end 24 thereon engageable with the dog 16 of the binder clutch 17. As shown, this stop member 19 is also provided with a slotted portion 25 to enable it to move relative to the usual transverse pipe 26 and is provided at its stubbleward end with an upwardly extending portion 27 which is pivotally connected by a sleeve connection 28 with the shaft 14 at a point adjacent and within the crank 13. The stop 19 is also provided with spaced arcuate lugs 29 and 30 disposed above its pivot and engageable with a cam 31 rotatable with the needle shaft 5. As shown, this stop 19 is also connected to the frame by means of a rod 32 pivoted at 33 on the binder head at a point above the pivot 20, and extending through a laterally extending lug 34 on the stubbleward end of the member 19, a coiled spring 35 being disposed about the protruding end of the rod and held in position thereon by an adjustable nut connection 36 by which the tension of the spring may be adjusted.

In the operation of my improved mechanism, it will, of course, be understood that the parts will occupy the position shown in full lines in Fig. 1 prior to the actuation of the trip 15. When, however, the pressure of the grain against this trip forces the

same backward, the end of the shaft 14 shown herein will be moved bodily toward the left from the position shown in full lines in that figure, to the position shown in dotted lines in that figure, the trip 15 likewise assuming the dotted line position. This movement, obviously, swings the stop 19 about its pivot 20, causing the same to assume the dotted line position shown in that figure, wherein the dog 16 of the clutch 17 is released to set the binding mechanism in operation. Obviously, the binding needle will then move upward through its normal path into engagement with the knotter carried on the head 1 (not shown), since, as in the usual construction, the clutch 17 connects the needle driving mechanism. As soon as the dog 16 is released, and during this upward and backward movement of the needle, the cam wheel 7 will be rotated as usual and the crank connection 12 thereof will be lowered in such a manner as to lower the trip 15 to the position shown in Fig. 2, wherein the grain bound by the needle may be discharged from the deck by the discharge arms 4 without conflict with the trip. During this movement it will be noted that the stop 19 is through its connections swung backward still farther about its pivot from the position shown in dotted lines in Fig. 1 to the position shown in full lines in Fig. 2, wherein it engages with the lug 28 on the binder head 1. Obviously, the stop member 19 will be held in that position by the action of the cam 31 on the lug 29 until after the clutch dog 16 has completed two revolutions, whereupon the cam wheel 7 will cause the connection 12 to again be raised to raise the trip 15, and since the needle has then returned to its normal position, shown in full lines in Fig. 1, under the action of the spring 35, the same will remain in that position during the remainder of the third revolution of the clutch dog 16 and interrupt the movement of that dog when the latter has completed its third revolution, the parts then being in their normal position and ready to bind another bundle.

In the operation of my improved mechanism, it will be noted that the trip stop has relatively little movement and a very small amount of wear upon the same, practically all wear being taken on surfaces of a character well adapted to long service. It is further to be noted that the construction is exceedingly simple, involving a small number of parts which may be very readily manufactured and assembled and that the mechanism requires little or no adjustment, the only part requiring any adjustment being the spring 35. Attention is also directed to the fact that the mechanism is such as to require a very small vibration of the trip arm 15 in order to set the same in operation, and that the amount of friction of the working

parts is relatively small as compared with ordinary binder mechanisms. These and many other advantages of my improved construction will, however, be apparent to those skilled in the art.

While I have in this application specifically described one embodiment which my invention may assume in practice, it is, of course to be understood that this form of the same is used for purposes of illustration and that the invention is not limited thereto, but may be embodied in various other arrangements and construction of the parts.

What I claim as my invention and desire to secure by Letters Patent is:

1. In a binding mechanism, a frame, a binder clutch, a bodily movable shaft on said frame, and a swinging clutch controlling member pivoted on said frame and controlled by said shaft.

2. In a binding mechanism, a frame, a binder clutch, a bodily movable shaft on said frame, and a swinging clutch controlling member pivoted on said frame and journaled on said shaft.

3. In a binding mechanism, a frame, sheaf binding and discharging mechanism thereon including a clutch, a compressor trip, a bodily movable trip shaft on said frame, and a swinging clutch controlling member controlled by said shaft.

4. In a binding mechanism, a frame, sheaf binding and discharging mechanism thereon including a clutch, a compressor trip, a bodily movable trip shaft on said frame, and a swinging clutch controlling member journaled on said shaft.

5. In a binding mechanism, a frame, sheaf binding and discharging mechanism thereon including a clutch, a compressor trip, a bodily movable trip shaft connected to said mechanism on said frame, and a swinging clutch controlling member journaled on said shaft.

6. In a binding mechanism, a bodily movable compressor trip shaft, a binder clutch, a clutch controlling member, and means whereby upon bodily movement of said shaft said clutch controlling member is oscillated into and out of engagement with said clutch.

7. In a binding mechanism, a binder frame, sheaf binding and discharging mechanism thereon including a clutch, a compressor trip, a trip shaft connected to said mechanism and movable bodily relative to said frame upon actuation of said trip, and a clutch controlling member pivoted on said head and operatively connected to said trip shaft.

8. In a binding mechanism, a binder frame, sheaf binding and discharging mechanism thereon including a clutch, a compressor trip, a trip shaft connected to said mechanism and movable bodily relative to

said head upon actuation of said trip, and a clutch controlling member pivoted on said head and journaled on said trip shaft.

9. In a binding mechanism, a binder frame, sheaf binding and discharging mechanism thereon including a clutch, a compressor trip, a shaft operatively connected to said trip and movable bodily relative to said frame upon actuation thereof, a swinging clutch controlling member pivoted on said head and controlled by said shaft, and means connected to said mechanism for holding said clutch controlling member out of operation for a predetermined time.

10. In a binding mechanism, a binder frame, sheaf binding and discharging mechanism thereon including a clutch, a compressor trip, a shaft operatively connected to said trip and movable bodily relative to said frame upon actuation thereof, a spring pressed swinging clutch controlling member pivoted on said head and controlled by said shaft, and means connected to said mechanism for holding said clutch controlling member out of operation for a predetermined time.

11. In a binding mechanism, a binder frame, sheaf binding and discharging mechanism thereon including a clutch, a compressor trip, a shaft operatively connected to said trip and movable bodily relative to said frame upon actuation thereof, a swinging clutch controlling member pivoted on said head and controlled by said shaft, and means connected to said binding mechanism for holding said clutch controlling member out of operation for a predetermined time.

12. In a binding mechanism, a binder frame, sheaf binding and discharging mechanism thereon including a clutch, a compressor trip, a trip shaft carrying said trip and movable bodily relative to said frame upon actuation of said trip, a clutch controlling member pivoted on said head and operatively connected to said trip shaft, means connected to said binding mechanism for holding said clutch controlling member out of operation for a predetermined time, and means for automatically returning said clutch controlling member to normal position.

13. In a binding mechanism, a binder frame, sheaf binding and discharging mechanism thereon including a clutch, a compressor trip, a trip shaft carrying said trip and movable bodily relative to said frame upon actuation thereof, a clutch controlling member pivoted on said frame and operatively connected to said trip shaft, means

connected to said binding mechanism for holding said clutch controlling member out of operation for a predetermined time, and adjustable resilient means for returning said clutch controlling member to its normal position.

14. In a binding mechanism, a binder frame, sheaf binding and discharging mechanism thereon including a clutch, a compressor trip, a trip shaft movable bodily with respect to said frame upon actuation of said trip, means connecting said shaft to said mechanism, an oscillating clutch controlling member pivoted on said frame and journaled on said shaft, and a rotating cam member movable with said binding mechanism and engageable with said clutch controlling member for a predetermined time.

15. In a binding mechanism, a frame, a trip shaft mounted thereon for bodily movement, a needle shaft journaled on said frame, a cam member on said needle shaft, a clutch mounted on said frame, and a clutch controlling member journaled on said frame at a point below said shaft having a portion journaled thereon and a portion at one side of said shaft engageable with the cam carried on said needle shaft.

16. In a binding mechanism, a binder frame, a bodily movable trip shaft carried thereon, a needle shaft journaled on said frame, a cam member carried on said needle shaft, a clutch controlling member pivoted on said frame beneath one of said shafts having an upwardly extending portion connected to said trip shaft and a portion engageable with said cam, and a resilient connection between said clutch controlling member and said binder frame.

17. In a binding mechanism, a binder frame, a bodily movable trip shaft thereon, a binder clutch on said frame, a needle shaft journaled on said frame between said trip shaft and said binder clutch, a cam carried on said needle shaft, a clutch controlling member pivoted on said frame beneath one of said shafts having a portion thereof operatively connected to said trip shaft and cam surfaces disposed on opposite sides of the cam on said needle shaft, means on said frame for limiting the movement of said clutch controlling member, a spring carrying rod journaled on said frame and extending through a portion of said clutch controlling member, a spring carried on the protruding end of said rod, and means for adjusting the tension of said spring.

In testimony whereof I affix my signature.
BERT R. BENJAMIN.
